FIRE ALARM AND PREVENTION SYSTEM

William L. Belknap, Stratford, Conn., assignor to
The Belknap Manufacturing Company, Bridge-
port, Conn., a corporation of Connecticut

Application July 8, 1935, Serial No. 30,254

9 Claims. (Cl. 137—162)

This invention relates to new and useful improvements in fire alarm and prevention systems, and has for an object to provide an effective system for cutting off the flow of fuel to a furnace or the like in the event of a fire, and which system also preferably includes means for sounding an alarm simultaneously with the cutting off of the fuel flow.

A particular object is to provide a construction 10 and arrangement which will be sure to operate in case of a fire.

Other objects and advantages will become apparent from a consideration of the following detailed description taken in connection with the 15 accompanying drawings wherein a satisfactory embodiment of the invention is shown. However, it will be understood that the invention is not limited to the details disclosed but includes all such variations and modifications as fall within the spirit of the invention and the scope of 20 the appended claims.

In the drawings:

Fig. 1 is a plan view illustrating one arrangement of the system in a basement or other room;

Fig. 2 is an elevational view on an enlarged 25 scale and showing details of construction;

Fig. 3 is an edge view showing the latching means employed;

Fig. 4 is a sectional view taken substantially 30 along the line 4—4 of Fig. 2;

Fig. 5 is an enlarged detail sectional view taken substantially along the line 5—5 of Fig. 2;

Fig. 6 is an enlarged sectional view through an example of a fusible element which may be employed;

Fig. 7 is a top plan view on an enlarged scale, showing a bell crank lever used in the system; and

Fig. 8 is an edge view of the bell crank of Fig. 7.

Referring in detail to the drawings at 10 is generally indicated a valve including a casing 11 having an inlet port 12 and also having an outlet port to a pipe 12a. Within the casing is a valve element 9 which is connected to lever 13 to be operated thereby, and which valve element normally occupies an open position as shown in the lower or dotted line position when elements 13 and 17 are in the elevated full line position of Fig. 2 permitting communication between the 15 inlet and outlet ports of the valve but which is adapted to be moved to a closed position (shown in dot and dash lines) to prevent such communication by lowering of elements 13 and 17 to the lower dotted position. The valve 10 is adapted 20 to be connected in an oil, gas or other fuel line 25 to

to a burner such as the burner of a furnace or the like and as will be hereinafter explained is adapted at the proper time to close such fuel line and cut off the flow of fuel therethrough.

A lever 13 is pivotally mounted on the valve casing as at 16 and has its outer end portion enlarged vertically and provided with upper and lower stops 15a and 15. Lever 13 is so connected with the valve element that when the lever is in the full line position of Fig. 2 the valve is open 5 but when the lever is in the broken line position of that figure the valve is closed. Pivoted to lever 13 at 16 is a weighted arm 17 the outer or free portion of which is preferably in the form of a ball-like weight and has integral therewith or secured thereto a hook 18 the purpose of which will later appear. The lever 17 is electrically insulated from lever 13 at pivot 16 in any suitable manner.

Interposed between the weighted arm 17 and the stop 15a is a coil spring 19 normally tending 10 to force the arm downwardly or in the direction of the stop 15. When the valve is open a suitable connection is made with the hook 18 to hold the arm 17 in an upper position and the arm is moved upwardly about its pivot 16 and relative to the lever 13 until the spring 19 is compressed 15 sufficiently so that the lever 13 moves upwardly with the arm shifting the valve to open position. Since the arm is movable relative to the lever it will be apparent that on the arm being released the spring 19 will assist the weighted outer end of the arm in swinging the latter downwardly about its pivot so as to have it strike the stop 15 a hammer-like blow. Therefore, if the pivot of the lever or the valve happens to be stuck or somewhat clogged with dust or the like, the same will be loosened so that the lever will swing downwardly and cause closing of the valve.

The present apparatus is adapted for installation in a basement or any other room or desired location and includes a bracket 20 comprising a base portion 21 to be secured to a ceiling or beam or the like as by screws 22 and a depending portion 23 carried by the portion 21. An arm 24 is pivoted to the bracket 20 at 25 and includes a downwardly extending portion 26 and a forwardly directed portion 27 which intermediate its ends is offset as at 28 to provide a shoulder and the free end 29 of which may be somewhat hook shaped 20 as shown. Also, pivotally mounted on the bracket by any suitable means such as a screw 30 is a latch 31 and the same is pivoted intermediate its ends and has an upper out-turned portion 32 25 provided with an opening or notch 33. As shown 30

latch 31 is formed of flat stock and has its lower end portion twisted through an angle of ninety degrees as at 34 and then has its extreme lower portion 35 bent to extend rearwardly but inclining downwardly somewhat as shown best in Fig. 2.

In the installation a wire generally designated 36 may be carried about a room or basement or may be located only about the furnace or other possible source of fire as desired. Fig. 1 shows one possible layout and there it will be noted that the wire comprises sections 37, 38, 39, 40 and 41 and that in each section at any likely or desired point there is included one or more fusible means 42 which may be of any suitable type there being shown by way of example one type the details of which are shown in Fig. 6. Wherever it is necessary to carry the wire around a corner or an obstruction, bell crank levers are employed instead of guides to reduce friction, and while such levers as here disclosed are all of the same construction the four shown in Fig. 1 are for the purpose of further description designated 43, 44, 45 and 46 respectively. These levers are pivotally mounted adjacent the corners about which the wire is to be taken and the pivots are designated 47.

Figs. 7 and 8 show the structure of one of the bell crank levers, that designated 43, and the same includes angularly disposed arms 48 and 49 connected by a hub portion 50 having an opening 51 therethrough for the passage of the pivot 47 shown as in the form of a screw. Each of the arms may or may not include a reenforcing or strengthening rib 48a as desired.

After the bell crank levers are in place the wire may be installed and in such installation one end of the section 41 of the wire is anchored as at 52 and its other end is connected with an arm of the bell crank lever 46 at 53. Wire section 41 may extend along a wall 54 of a room and the section 40 extends along the wall 55 at right angles to the wall 54 and has an end connected at 56 with the other arm of bell crank lever 46 and then has its opposite end connected at 57 with an arm of the bell crank lever 45. Wire section 39 extends along the wall 58 and at 59 has an end connected with an arm of the lever 45 and at 60 has an end connected with an arm of the lever 44. The wall 61 is comparatively short as is the wire section 38 extending along it and attached at 62 to an arm of the lever 44 and at 63 to an arm of the lever 43.

The wire section 37 has one end connected 55 with the other arm of the lever 43 at 64 and the other end of such wire is connected with one end of a coil spring 65 and there may be interposed a fusible means 42. At desired spaced points supporting eyes 66 may be screwed into the ceiling and have the wire pass through them as in Fig. 2. The other end of the spring 65 is hooked through the opening 33 in the upper portion of the latch 31. The arrangement is such that the end of the wire 36 being anchored at 52 the spring 65 is tensioned when all the parts are in normal position, and cooperating with the arm 24 holds the latch 31 in normal position which is the position it is shown in in Fig. 2.

A wire 67 is connected at its lower end with 70 the hook 18 of the arm 17 and at its upper end is connected with the lower end of a coil spring 68 by means of one of the fusible means 42. The upper end of the coil spring 68 is connected with the hook like portion 29 of the arm 24. The means 69 which connects the lower end of the

wire with the hook 18 comprises a flat insulating member made of fibre board or the like. It is the same as member 70 having similar spaced openings, as shown in member 70 in Fig. 3, for the passage of the wire and the hook and adapted to be manually connected with and removed from the hook. The member 70 connects the upper end of the spring with the arm 24, and as shown more particularly in Fig. 3 has a large opening 71 for the passage of the hook portion of said arm 10 and a smaller opening 72 through which the upper end of the spring is passed.

The full lines in Fig. 2 show the relationship of the parts when the valve 19 is in normal or open position. There it will be noted that the lever 13 and arm 17 are being held in their upper position and that the shoulder formed by the offset portion 28 of the arm 24 is bearing against the upper inclined surface of the lower portion 35 of the latch 31. Also, the vertical portion of said latch is being held in abutting engagement with the offset portion 28 of the arm 24 as shown at 73. Spring 65 is tensioned as above stated and is tending to rock the latch in a direction to carry its lower portion toward the arm 24. Spring 68 is also tensioned and is drawing downwardly on the arm 24 but is prevented from moving it owing to the fact that the offset portion 28 of the arm is disposed on the upper inclined surface of the portion 35 of the latch, the tension of spring 65 being sufficient to prevent the camming action of the shoulder of the offset 30 28 on inclined portion 35 due to spring 68 from shifting the lever or catch 31 to release arm 24.

On a predetermined rise in the temperature in 35 its vicinity any one of the means 42 will fuse or release. Should the means 42 connecting wire 67 and spring 68 release the arm 17 will be released and the spring 19 will act to force such arm downwardly about the pivot 16. Also, owing to 40 the weight on its outer end the arm tends to gravitate downwardly immediately on being released but it will be appreciated that spring 19 accelerates this movement. As the arm moves downwardly it gains considerable momentum and so strikes the stop 15 a hammer-like blow to jar the lever 13 loose if its pivot tends to stick and the lever then moves downwardly with the arm until the parts assume the broken line position of Fig. 2 in which the valve is closed.

Should one of the means 42 in the wire 36 fuse the parts of the wire connected by such means will separate owing to the tension placed on the wire by the spring 65. When this occurs the spring is released or is free to return to its normal condition and in contracting draws the wire with it. This, it may easily do since it is not required that the wire be drawn through or over a plurality of supports or the like as the various bell crank levers will rock about their pivots when a portion of the wire is released and there is the pull on its other portion, and will so permit the spring to contract.

As the spring is permitted to contract or is released the pull on the latch 31 maintaining it in 65 abutting relation with the arm 24 at 73 ceases. However, the spring 68 is still under tension and tending to draw the arm downwardly by forcing its portion 28 against the upper inclined surface of the portion 35 of the latch causes the latch to swing in a counter-clockwise direction releasing the arm 24. On the latter being released it swings toward the broken line position of Fig. 2 permitting the connecting member 70 to slip off the end of the hook portion 29. In this way the 70 75

means including wire 67 and spring 68, supporting the arm 17 in its upper position, is released and the arm and lever 13 are free to move downwardly closing the valve as above explained. 5 With this arrangement it is not necessary for the spring 68 to pull lengths of wire through a series of guides if a fusible element at some remote point releases, but the pull of the wire is by spring 65 which may be made as strong as desired. 10 However, as soon as spring 65 is released the catch 24, 31 releases under action of spring 68 and permits the valve to close.

The fusible means 42 which is shown merely by way of example, each comprise inner and 15 outer sleeves 74 and 75, an intermediate body portion 76, and eye members 77 the shanks of which are screwed into the inner sleeve 74 made of separable sections. Between this latter sleeve and outer sleeve 75 is a fusible portion 76 and 20 it will be apparent that on fusing of the portion 76 the sleeve 74 separates the eyes 77 are no longer connected and any wires connected by the means may be pulled apart. Owing to the fact 25 that the shanks of the eyes are screwed into the sleeve 74 the eyes may be turned relatively to bring them into the desired angular relationship.

Means are provided for sounding an alarm in the event of the closing of the valve 10. This means includes a contact pin 78 projecting 30 through a housing 79 carried by the arm 17 and also projecting through such arm to extend at the side thereof toward the lever 13. The pin is insulated from the arm 17 by a bushing-like member 80 and a similar member 81 insulates the 35 pin from the housing 79. About the pin within the housing is a spring 82 bearing at one end against the insulation 81 and at its other end against a collar 83 on the pin and normally maintaining said collar against the bushing 80. In 40 its inner face lever 13 is provided with a groove or recess 84 opposite the projecting end of the pin 78 when the parts are in normal position whereby under normal conditions the pin does not contact with the lever. An inclined wall 84a leads downwardly from this recess.

The connections for the alarm feature of the system are shown in Fig. 2 wherein 85 is a transformer connected to the house wiring system by leads 86 and by a wire 87 connected with the 50 contact pin 78 of the arm 17. Wire 88 connects the transformer with one binding post of an alarm such as the bell 89 and a wire 90 connects the other contact of such alarm with the valve casing 11 or lever 13 or some other part conductively connected with such lever to form a 55 ground.

When the arm and lever are in their normal relation the contact pin 78 is spaced from the lever by reason of being opposite the notch or 60 recess 84 of the lever as shown in Fig. 5. However, on the arm 17 being released owing to the fusing of one of the fusible means 42 the arm 17 swings downward relatively to the lever 13 as previously explained so that the inner end of the 65 contact pin is brought against the inclined wall 84a of the lever closing a circuit to the alarm signal 89. Obviously, the means 89 may take the form of a light or of any other type of signal, audible or otherwise, but is preferably a bell or 70 similar alarm so as to arouse members of the household in case of fire.

Having thus set forth the nature of my invention, what I claim is:

1. In combination, a normally open valve, 75 means normally tending to move the valve to

closed position, a tensioned wire, means constantly tensioning said wire, a latch means held in latching position by said wire, a connection between said latch and valve to maintain said valve in open position, and a fusible means in 5 the length of said wire and adapted on a predetermined rise in temperature to fuse and release the wire whereby said latch moves from latching position releasing said valve.

2. In combination, a normally open valve, 10 means tending normally to move the valve to closed position, a pivoted arm, means connected with the valve and arm and holding the valve in open position and adapted to be released by the arm on movement of the latter about its pivot, 15 a pivoted latch engaging and maintaining said arm against such movement, and means including a fusible means normally holding said latch in position preventing movement of said arm and a spring between the latch and the fusible 20 element constantly tensioning said latch holding means.

3. In combination, a normally open valve, a lever connected to move said valve to closed position, means tending normally to move the 25 lever and close the valve, a pivoted arm, means connected with the lever and arm and supporting the lever with the valve in open position and adapted to be released by the arm on movement of the latter about its pivot, a pivoted latch engaging and maintaining said arm against such movement, means including a tensioned wire 30 normally holding said latch in position preventing movement of said arm, and a fusible means in the length of said wire. 35

4. In combination, a normally open valve, means tending normally to move the valve to closed position, a pivoted arm, means including a tensioned spring connected with the valve and arm and retaining the valve in open position 40 and adapted to be released by the arm on movement of the latter about its pivot, a pivoted latch engaging and maintaining said arm against such movement, and means including a fusible means normally holding said latch in position 45 preventing movement of said arm.

5. In combination, a normally open valve, means tending normally to move the valve to closed position, a pivoted arm, means connected with the valve and arm and maintaining the 50 valve in open position and adapted to be released by the arm on movement of the latter about its pivot, a pivoted latch engaging and maintaining said arm against such movement, and means including a tensioned spring and a 55 fusible means normally holding said latch in position preventing movement of said arm.

6. In combination, a normally open valve, a lever connected to move said valve to closed position, means tending normally to move the lever and close the valve, a pivoted arm, means including a tensioned spring connected with the lever and arm and supporting the lever with the valve in open position and adapted to be released by the arm on movement of the latter about its pivot, a pivoted latch engaging and maintaining said arm against such movement, and means including a tensioned spring and a 65 fusible means normally holding said latch in position preventing movement of said arm.

7. In combination, a normally open valve, means tending normally to move the valve to closed position, a pivoted latch including an inclined surface portion, means including a fusible means maintaining said latch in normal po- 75

- sition, a pivoted arm including a portion resting on said inclined surface when the parts are in normal position, a connection between the arm and the valve whereby when said arm is in normal position it maintains the valve open, and said connection including a tensioned spring whereby when said latch is released it is cammed out of normal position releasing the arm.
8. In combination, a normally open valve, means tending normally to move the valve to closed position, a pivoted latch including an inclined surface portion, means including a spring tensioned wire to maintain said latch in normal position, a fusible means in the length of said wire and connecting the ends of a pair of sections thereof, a pivoted arm including a portion resting on said inclined surface when the parts

are in normal position, a connection whereby when said arm is in normal position it maintains the valve open, and said connection including a tensioned spring whereby when said latch is released it is cammed out of normal position releasing the arm. 5

9. In combination, a normally open valve, a lever connected to move said valve to closed position, means tending normally to move the lever to close the valve, a latch means, a connection between the latch means and the lever normally holding the lever in position with the valve open, spring means tending to move said latch means from normal position to release the lever, and a fusible means holding the latch means in normal position. 10 15

WILLIAM L. BELKNAP,
